UNITED STATES PATENT OFFICE.

EDWIN A. PETERSON, OF MADISON, WISCONSIN, ASSIGNOR TO VINCENT CAMARATA, JOHN CODRICK, AND RAYMOND P. DANLEY, ALL OF PHILADELPHIA, PENNSYLVANIA.

SUCTION CLEANER.

Application filed February 7, 1921. Serial No. 443,101.

To all whom it may concern:

Be it known that I, EDWIN A. PETERSON, a citizen of the United States, residing at Madison, in the county of Dane and State 5 of Wisconsin, have invented certain new and useful Improvements in Suction Cleaners, of which the following is a specification.

This invention relates to a suction cleaner of the portable type for cleaning rugs and 10 the like.

One of the objects of the present invention is to provide a suction cleaner which is power-driven, in its sweeping movement, back and forth upon the rug thus reducing the 15 amount of energy required of a person to operate the same to a minimum degree.

Another feature of the invention resides in providing a suction cleaner of the above-mentioned character wherein a single motor 20 actuates the suction impeller, a sweeping brush and also moves the suction cleaner back and forth in its sweeping movement, thereby providing a very simple construction for performing the three functions simultaneously.

Still another feature consists in the manner of accomplishing the backward and forward movement of the cleaner without reversing the motor that drives the same.

Another very important feature consists 30 in the provision of a reducing gear between the motor and the wheels of the suction cleaner, whereby the motor is permitted to run at its normal high speed without driving the suction cleaner back and forth across the floor at an abnormal rate.

In the drawings:

Figure 1 is a phantom side elevation of a 40 suction cleaner construction in accordance with the present invention;

Figure 2 is a top plan view of the mechanism removed from the casing;

Figure 3 is a side elevation of the mechanism removed from the casing;

Figure 4 is a fragmentary elevation and part section of the reducing gearing.

In detail:

The invention, as herein shown for the 50 purpose of illustrating the principles of the same, comprises a casing indicated in general at A and having a barrel portion 1 forming a motor housing, an annular for-

ward portion 2 forming an impeller housing and a sweeping head 3.

Within the barrel 1 are pedestals 4 and 5 which mount a motor 6 having its shaft 7 concentric with the annular impeller casing 2. The forward end of the shaft 7 carries the impeller 8 of the usual form and which 60 draws air through the sweeping head 3. The front of the impeller casing 2 is closed by a cover plate 9 which permits of access to the impeller. The screws 10 serve to connect the barrel 1 with the impeller housing 2.

Within the sweeping head 3 is journaled a shaft 11 carrying a brush 12 with tufts 13; said shaft also having a pulley 14 for purposes to be hereinafter fully set forth.

Bearings 15 at the rear of the barrel 1 mount an axle 16 carrying a bevel gear 17 provided with a pulley face 18 which latter is connected by a belt 19 to drive the pulley 14 on the brush shaft 11 as the suction 75 cleaner or sweeper traverses the floor. At each end the axle 16 carries a suitable wheel 20 keyed thereto. Meshing with the bevel gear 17 is a pinion 21 carried by a sleeve 22 supported in a bearing 23 in the 80 barrel 1. The top of said sleeve is flanged as indicated at 24 to receive and journal the gears 25 of a reducing gearing, the driving gear 26 of which is carried by a shaft 27 journalled in the sleeve 22 and in a bearing 85 28 see Figure 4. The upper end of the shaft 27 is provided with a friction cone 29.

The motor shaft 7 is extended rearwardly and has slidably keyed thereon, as indicated at 30, a spool 31 carrying opposite friction faces 32 and 33 of conical form and adapted to be engaged in driving relation with the friction cone 29.

In order to move the spool 31 so that either face 32 or 33 may be selectively engaged 95 with the friction cone 29, a fork 34 engages in the slot 35 in the said spool and is connected with a lever 36 pivotally swung at 37 intermediate its ends, one end 38 being connected as stated with the upper end of the fork 34, while the other end carries an armature 39 located between the poles of two solenoids 40 and 41. These solenoids are connected in circuit with a source of electrical energy and a double throw switch 43 mounted on the handle 44 and which is of

the sliding type and may be operated by movement of the index finger, as clearly shown in Figures 1 and 3.

In operating the suction cleaner or sweeper, the operator grasps the handle 44 in the usual manner with the index finger resting on the plate of switch lever 43 which is slideable on said handle to move the lever 43 into contact with switch point 46 or 47, as desired.

If the switch lever 43 be moved to contact with switch point 46, the solenoid 40 will be energized with the result that armature 49 will be attracted thereto and draw the conical face 32 into contact with the friction cone 29 driving the axle 16 in one direction, while the opposite movement moves the lever 36 in the opposite direction to drive the machine oppositely.

However, it is to be noted, that no matter which direction the machine is moving across the floor, the motor 4 is always running in the same direction, while the brush 12 is reversed to run as it should run for the selected direction of movement of the suction sweeper.

A separate switch of any suitable type may be incorporated in the handle, as for instance a turn button switch as indicated at 57 for feeding current to the electric motor 6.

While in the foregoing I have described a specific embodiment of the invention, it is nevertheless to be understood, that, in carrying the same into practice, various modifications and arrangements of the driving mechanism or the axle and brush may be employed without departing from the scope of the invention.

I claim:

1. A suction cleaner comprising a suction nozzle, fan chamber and transmission housing arranged in the order named, a suction fan in said chamber, traction wheels sup-

porting said housing, and a motor driven transmission mechanism including a reducing gearing mounted in said housing for driving said fan and wheels simultaneously, the latter through the intermediary of said reducing gearing.

2. A suction cleaner comprising a suction nozzle, fan chamber and transmission housing arranged in the order named, a suction fan in said chamber, traction wheels supporting said housing, a motor driven transmission mechanism including a reducing gearing mounted in said housing for driving said fan and wheels simultaneously, the latter through the intermediary of said reducing gearing, a revoluble brush in said suction nozzle, and driving connection between said wheels and said brush, said transmission also including a reversing gearing.

3. A suction cleaner comprising a suction nozzle, a fan chamber and a motor casing arranged in the order named, a motor in said motor casing, a fan in said fan chamber operatively connected with said motor, traction wheels mounted on and supporting said cleaner and transmission mechanism including a reducing gearing operatively connecting the motor and traction wheels.

4. A suction cleaner comprising a suction nozzle, a fan chamber and a motor casing arranged in the order named, a motor in said motor casing, a fan in said fan chamber operatively connected with said motor, traction wheels mounted on and supporting said cleaner and transmission mechanism including a reducing and reversing gearing operatively connecting the motor and traction wheels.

In testimony whereof I affix my signature.

EDWIN A. PETERSON. [L. S.]
